HOLDER FOR LIP STICKS OR THE LIKE

Irving Florman, New York, N. Y.

Application November 5, 1935, Serial No. 48,403

7 Claims. (Cl. 206—56)

My invention relates to holders for cosmetics in stick form, and particularly for lipsticks.

The primary object of my invention is to provide a simple arrangement of holder for lipsticks or the like, which ejects the stick from the holder into a position for use with a single easy movement of the hand.

While such devices have heretofore been made, the present arrangement is provided with means which will prevent the holder from opening accidentally, and yet will permit easy manual operation.

Still another object of the invention is to provide a lipstick holder having a cover, in which movement of the cover ejects the lipstick into a position for use. More particularly, the invention contemplates an arrangement of this type in which the cover moves down the side of the container so as to provide a somewhat wider device adapted for easier holding by the user when the lipstick is being applied.

Further objects and advantages of my invention will appear more fully from the following description particularly when taken in conjunction with the following drawings which form a part thereof.

In the drawings:

Fig. 1 is a side view with parts broken away of a device according to my invention in partly open position.

Fig. 2 is a similar view of the device in fully open position.

Fig. 3 is a rear view of the same.

Fig. 4 is a top plan view of the device in the position shown in Fig. 2 with parts broken away.

Fig. 5 is a cross section substantially on the line 5—5 of Fig. 4.

Fig. 6 is a cross section on the line 6—6 of Fig. 3.

Fig. 7 is a vertical cross section through the device in closed position.

Fig. 8 is a cross section on the line 8—8 of Fig. 6.

Figs. 9 and 10 are cross sections on the lines 9—9 and 10—10 respectively of Fig. 7.

The holder according to my invention comprises a container having a front wall 2, side walls 4 and a rear wall 6, this container being open at its top. Preferably the container has the shape of an elongated rectangle, in general similar to the shape of the usual lipstick. The upper portion of the rear wall 6 of the container is provided with two slots 8 at either side thereof extending from the top edge of this wall downwardly to or past the center thereof, leaving

therebetween a tongue 10. The purpose of these slots will be explained below.

Within the container is arranged a tube-like member 12 of slightly smaller outer dimensions than the inner dimensions of the container, and of substantially the same height. The side walls of the member 12 are each provided with a horizontal slot 14. The rear wall of the tube-like member 12 is secured by screws 16 to the rear wall 6 of the container. The width of the member 12 is substantially equal to the width of the tongue 10 between the slots 8, and the outer surfaces of the side walls of member 12 are aligned with the inner edges of these slots. From the front wall of the member 12 adjacent the top thereof are struck out two members to form a tongue or stop 18, the purpose of which will be described below.

Slidably fitting in the tube-like member 12 is a holding member 20 in which may be secured 20 a rod-like portion 22 of lipstick or any other material. This member 20 is provided in each side wall and below the portion which grips the lipstick with inclined or diagonal slots 24. The horizontal length of each of these slots is substantially equal to the length of the slots 14.

An operating member 26 is slidable on the outside of the tube-like member 12, within the space between the walls of such tube-like member and the walls of the container. Member 26 has side walls 28 and a front wall 30. The front wall 30 connects the bottom portions of the side walls 28, but is cut away at the front. The side walls 28 are provided at their upper end with an upward and rearward extension 32 on which is pivoted at 34 a cover 36, this cover being of such a size as to fit on the upper end of the container. The projecting portions 32 are in alignment with the slots 8 in the rear wall 6 of the container. Thus the member 26 may be moved up and down in the container, with the projections 32 traveling in the slots 8.

Each side wall 28 of the member 26 is provided with a slot having a lower vertical portion 38 located on the opposite side from the lower end 45 of slot 24 and a diagonal portion 40 extending transversely to the slot 24. A pin 42 is arranged to pass through the slots 14, 24 and 40. This pin acts as a force transmitting member so that upon upward or downward movement of the 50 member 26, pin 42 will be shifted laterally in slot 14 because of the cam action of the inclined slot 40, and will impart vertical movement to holding member 20 because of the inclined slot 24. It is thus evident that if the cover is pushed side- 55

ward and downward from the position shown in Fig. 5 to the position shown in Fig. 6 the holding member 20 will be raised and the lipstick will be ejected into a position for use. The length 5 of the portion of the lipstick which is brought out of the container may be easily determined by varying the movement of the cover 36.

In order to prevent accidental opening of the cover, means are provided to hold the same resiliently in closed position. A spring operating 10 or engaging member 43 is arranged between the front wall of the tube-like member 12 and the front wall 2 of the container. The member 43 consists of a trough shaped element having a tongue 44 struck inwardly in the lower portion 15 thereof, and a flange 45 at its top above the tongue 18 to limit its downward movement. The member 43 is arranged to overlie and enclose the tongue 18 on the front wall of member 12. A coil compression spring 46 is arranged within the 20 trough-like member 43 between the tongues 18 and 44.

The front wall 30 of the member 26 is so dimensioned that as the member 26 approaches its 25 raised position wall 30 will engage the lower end of trough-like member 43. When the cover is in closed position, spring 46 is slightly compressed in this fashion. Any attempt to raise the cover imparts a slight upward movement to the member 26 because the cover tends to hinge about its lower rear edge and thus to raise the pivot 34 at the same time to tilt the member 28 backward. This lifts the front edge of the member 28 and thereby compresses the spring 46 still further. In 30 other words, in order to raise the cover it is necessary to overcome the pressure of spring 46. The spring therefore tends to hold the cover in closed position and prevents accidental opening of the holder. As soon, however, as the cover has been 40 opened and starts to move downwardly, the pressure of spring 46 is entirely released and the device may be moved freely and held in any desired position without the resistance of any spring.

45 While I have described herein one embodiment of my invention, I wish it to be understood that I do not intend to limit myself thereby except within the scope of the appended claims.

I claim:

50 1. In a lipstick holder or the like, a casing open at its top, a holding member slidably mounted in said casing, a cover for closing said casing, an element vertically slidable in said casing, means pivotally supporting said cover on said 55 element whereby the cover may move from a position above and closing the casing to a position at the side of the casing, means operated by movement of said cover and element to move said holding member so as to eject and withdraw 60 the holding member from the casing as the cover is moved, and means engaged by said element adjacent the upper end of its movement for resiliently resisting such movement, whereby to hold said cover in closed position.

65 2. In a holder for lipsticks or the like, a casing open at its top, said casing having a rear wall and slots in said rear wall extending downwardly from the upper edge thereof, an element fixed in said casing, said element having horizontal slots 70 in the side walls thereof, said element being of smaller dimensions than the inner dimensions of said casing, a holding member slidable in said element and having diagonal slots in the side walls thereof, an operating member vertically slidable 75 in said casing on the outside of said element,

said operating member having diagonal slots in the side walls thereof transverse to the diagonal slots in said holding member, a pin passing through the slots in said element, holding member and operating member, whereby upward movement of said operating member causes downward movement of said holding member and vice versa, the side walls of said operating member having rearward extensions adjacent the top edges thereof, said extensions being opposite and 10 adapted to move in the slots in the rear wall, and a cover pivoted on said extensions adjacent the rear wall of the casing, whereby when said cover is pivoted and moved down the rear wall of the casing said holding member is raised to 15 eject the lipstick or the like, and when said cover is moved upwardly to the top of the casing the holding member is moved downwardly to withdraw the lipstick.

3. In a holder for lipsticks or the like, a casing 20 open at its top, an element fixed in said casing, a tongue on said element, said element being of smaller dimensions than the inner dimensions of said casing, a holding member slidable in said element, an operating member vertically slidable 25 in said casing on the outside of said element, said operating member having side walls and a front wall connecting the lower portions of said side walls and of less height than the side walls, means connecting said element and said 30 members whereby upward movement of said operating member causes downward movement of said holding member and vice versa, a cover pivoted on said operating member, whereby when said cover is pivoted and moved down the rear wall 35 of the casing said holding member is raised to eject the lipstick or the like, and when said cover is moved upwardly to the top of the casing the holding member is moved downwardly to withdraw the lipstick, a spring engaging member 40 overlying the tongue on said element and having a tongue below the first tongue, and a coil compression spring between said two tongues, the front wall of said operating member engaging the lower edge of said spring engaging member when 45 the operating member moves upwardly, whereby to compress the spring when the cover is in closed position above the casing, whereby said cover is resiliently held in closed position to prevent accidental opening thereof.

4. In a holder for lipsticks or the like, a casing open at its top, said casing having a rear wall and slots in said rear wall extending downwardly from the upper edge thereof, a tube-like member 55 in said casing fixed to the rear wall thereof, said tube-like member having horizontal slots in the side walls thereof, said tube-like member being of smaller dimensions than the inner dimensions of said casing, a holding member slidable in said tube-like member and having diagonal slots in 60 the side walls thereof, an operating member vertically slidable in said casing on the outside of said tube-like member, said operating member having side walls and a front wall connecting the lower portions of said side walls and of less 65 height than the side walls, the side walls of said operating member each having a slot therein comprising a substantially vertical lower portion and a diagonal upper portion transverse to the diagonal slot in said holding member, a pin passing through the slots in said tube-like member, holding member and operating member, whereby upward movement of said operating member causes downward movement of said holding member and vice versa, the side walls of said operat- 70 75

ing member having rearward extensions adjacent the top edges thereof, said extensions being opposite and adapted to move in the slots in the rear wall, and a cover pivoted on said extensions adjacent the rear wall of the casing, whereby when said cover is pivoted and moved down the rear wall of the casing said holding member is raised to eject the lipstick or the like, and when said cover is moved upwardly to the top of the

10 casing the holding member is moved downwardly to withdraw the lipstick.

5. In a holder for lipsticks or the like, a casing open at its top, said casing having a rear wall and slots in said rear wall extending downwardly from the upper edge thereof, a holding member 15 slideable in said casing, an operating member vertically slideable in said casing outside of said holding member, means connecting said members whereby upward movement of said operating member causes downward movement of said holding member and vice versa, the side walls of said operating member having rearward extensions adjacent the top edges thereof, said extensions being opposite and adapted to move in the slots 20 in the rear wall, and a cover pivoted on said extensions adjacent the rear wall of the casing, whereby when said cover is pivoted and moved down the rear wall of the casing said holding member is raised to eject the lipstick or the like, and when said cover is moved upwardly to the 25 top of the casing the holding member is moved downwardly to withdraw the lipstick.

6. In a holder for lipsticks or the like, a casing open at its top, said casing having a rear wall and slots in said rear wall extending downwardly from the upper edge thereof, an element fixed in said casing, a tongue on the front wall of said element, said element being of smaller dimensions than the inner dimensions of said casing, a holding member 30 slideable in said element, an operating member vertically slideable in said casing on the outside of said element, said operating member having side walls and a front wall connecting the lower portions of said side walls and of less height than the side walls, means connecting said members whereby upward movement of said operating member causes downward movement of said holding member and vice versa, the side walls of said operating member having rearward extensions 35 adjacent the top edges thereof, said extensions being opposite and adapted to move in the slots in the rear wall, a cover pivoted on said extensions adjacent the rear wall of the casing, whereby when said cover is pivoted and moved down the rear wall of the casing said holding member is raised to eject the lipstick or the like, and when said cover is moved upwardly to the top of the casing the holding member is moved 40 downwardly to withdraw the lipstick, a spring engaging member overlying the tongue on the front wall of said tube-like member and having a tongue below the tongue on the tube-like member and a flange above the tongue on the tube-like 45 member, and a coil compression spring between said two tongues, the front wall of said operating member engaging the lower edge of said spring engaging member when the operating member moves upwardly, whereby to compress the spring 50 when the cover is in closed position above the casing, whereby said cover is resiliently held in closed position to prevent accidental opening thereof.

the first tongue and a coil compression spring between said two tongues, the front wall of said operating member engaging the lower edge of said spring holding member when the operating member moves upwardly, whereby to compress the 5 spring when the cover is in closed position above the casing, whereby said cover is resiliently held in closed position to prevent accidental opening thereof.

7. In a holder for lipsticks or the like, a casing 10 open at its top, said casing having a rear wall and slots in said rear wall extending downwardly from the upper edge thereof, a tube-like member in said casing fixed to the rear wall thereof, said tube-like member having horizontal slots in the 15 side walls thereof, a tongue on the front wall of said tube-like member, said tube-like member being of smaller dimensions than the inner dimensions of said casing, a holding member slideable in said tube-like member and having diagonal slots in the side walls thereof, an operating member vertically slideable in said casing on the outside of said tube-like member, said operating member having side walls and a front wall connecting the lower portions of said side walls and 20 of less height than the side walls, the side walls of said operating member each having a slot therein comprising a substantially vertical lower portion and a diagonal upper portion transverse to the diagonal slot in said holding member, a 25 pin passing through the slots in said tube-like member, holding member and operating member, whereby upward movement of said operating member causes downward movement of said holding member and vice versa, the side walls of 30 said operating member having rearward extensions adjacent the top edges thereof, said extensions being opposite and adapted to move in the slots in the rear wall, a cover pivoted on said extensions adjacent the rear wall of the casing, 35 whereby when said cover is pivoted and moved down the rear wall of the casing said holding member is raised to eject the lipstick or the like, and when said cover is moved upwardly to the top of the casing the holding member is moved 40 downwardly to withdraw the lipstick, a spring engaging member overlying the tongue on the front wall of said tube-like member and having a tongue below the tongue on the tube-like member and a flange above the tongue on the tube-like 45 member, and a coil compression spring between said two tongues, the front wall of said operating member engaging the lower edge of said spring engaging member when the operating member moves upwardly, whereby to compress the spring 50 when the cover is in closed position above the casing, whereby said cover is resiliently held in closed position to prevent accidental opening thereof.

IRVING FLORMAN. 60
